(57) **CLAIM**

The ornamental design for a connector, as shown and described.

DESCRIPTION

FIG. 1 is a front side view of a connector, showing my new design;

FIG. 2 is a left side view thereof with the front side up;

FIG. 3 is a rear side view thereof;

FIG. 4 is a right side view thereof with the front side up;

FIG. 5 is a bottom view thereof;

FIG. 6 is a top view thereof; and,

FIG. 7 is a perspective view thereof.

The broken line in the drawing views is included to show unclaimed environment only and forms no part of the claimed design.
